(57) **CLAIM**

I claim the ornamental design for an handheld animal waste collection apparatus, as shown and described.

DESCRIPTION

FIG. 1 is a rear elevation view of a handheld animal waste collection apparatus in accordance with the present design; FIG. 2 is a front elevation view of the apparatus of FIG. 1; FIG. 3 is a side elevation view of the apparatus of FIG. 1; FIG. 4 is a bottom view of the apparatus of FIG. 1; FIG. 5 is a top view of the apparatus of FIG. 1; FIG. 6 is a rear upper perspective view of the apparatus of FIG. 1; FIG. 7 is a rear lower perspective view of the apparatus of FIG. 1; FIG. 8 is a front upper perspective view of the apparatus of FIG. 1; FIG. 9 is a front lower perspective view of the apparatus of FIG. 1; FIG. 10 is a rear elevation view of the handheld animal waste collection apparatus according to a second embodiment; FIG. 11 is a front elevation view of the apparatus of FIG. 10; FIG. 12 is a side elevation view of the apparatus of FIG. 10; FIG. 13 is a bottom view of the apparatus of FIG. 10; FIG. 14 is a top view of the apparatus of FIG. 10; FIG. 15 is a rear upper perspective view of the apparatus of FIG. 10; FIG. 16 is a rear lower perspective view of the apparatus of FIG. 10; FIG. 17 is a front upper perspective view of the apparatus of FIG. 10; FIG. 18 is a front lower perspective view of the apparatus of FIG. 10; FIG. 19 is a front upper perspective view of the receptacle component in the FIGS. 1, 10 and 29 embodiments of the handheld animal waste collection apparatus; FIG. 20 is a rear perspective view thereof; FIG. 21 is a front lower perspective view thereof; FIG. 22 is a first rear upper perspective view thereof; FIG. 23 is a second rear upper perspective view thereof; FIG. 24 is a top view thereof; FIG. 25 is a bottom view thereof; FIG. 26 is a side elevation view thereof; FIG. 27 is a front elevation view thereof; FIG. 28 is a rear elevation view thereof;

(Continued)

FIG. 29 is a rear elevation view of the handheld animal waste collection apparatus according to a third embodiment; FIG. 30 is a front elevation view of the apparatus of FIG. 29; FIG. 31 is a side elevation view of the apparatus of FIG. 29; FIG. 32 is a bottom elevation view of the apparatus of FIG. 29;

FIG. 33 is a top elevation view of the apparatus of FIG. 29; FIG. 34 is a rear upper perspective view of the apparatus of FIG. 29;

FIG. 35 is a rear lower perspective view of the apparatus of FIG. 29; and,

FIG. 36 is a front upper perspective view of the apparatus of FIG. 29.

The handle stems of the handheld animal waste collection apparatus are shown with a symbolic break in length. The appearance of any portion of the article between the break lines forms no part of the claimed design.
